RECTIFIER

Ernst Albert Emanuel Törnblom, Malmö, Sweden,
assignor to Ingenjörsfirman C. A. C., Törnblom
& Björklund, Stockholm, Sweden

Application May 26, 1932, Serial No. 613,733
In Sweden March 23, 1932

17 Claims. (Cl. 175—364)

This invention relates to rectifiers adapted to rectify alternating electric currents to direct currents. To be a little more specific the invention relates to a rectifier of the kind having a field 5 rotating synchronously with the frequency of the alternating current and adapted to drive a contact body at a synchronous speed, the said contact body cooperating, in working position, with commutating means connected with the phases of the alternating current. In apparatus of the kind referred to it has been customary to provide a special starting motor adapted to start the contact body and to accelerate the mass of the body to a speed synchronous with the rotary field. 10 Only at the moment when the mass of the contact body reaches full synchronous speed the rotary field itself will be able to drive the body and to maintain its speed at the synchronous value, so that the starting motor may be switched off. 15 The primary object of the invention is to avoid the necessity of such starting motor and for this purpose I provide means for guiding the contact body during the starting period to cause the said body to move successively from a central 20 position of rest to a position in which the body engages the commutating means. By the aid of said guiding means and under the influence of the rotary field the contact body is caused to roll during the starting period on a helical line, 25 initiating at the central position of the contact body and terminating at the position engaging with the commutators. Under such conditions the rotary field itself can start the contact body from the position of rest in which the radius 30 of the path of the rolling movement of the contact body is zero or near zero, the radius then increasing successively to a predetermined value in the position engaging the commutators and consequently the necessary energy for overcom- 35 ing the inertia of the mass of the contact body in its position of rest is sufficiently reduced to enable the rotary field to drive the said mass at a synchronous speed already in the starting 40 moment without using any auxiliary starting motor. The contact body is then guided successively in a helical path towards its commutat- 45 ing position.

Further objects and advantages of the invention will be described with reference to the accompanying drawings which illustrate the invention in some preferred embodiments and in which

Figure 1 represents a diagrammatical view of 50 a rectifier embodying my invention,

Figure 2 a preferred embodiment of a magnet suitable for use in the apparatus,

Figures 3 and 4 horizontal and vertical sections respectively of a constructional form of a contact apparatus forming part of the rectifier, 60

Figure 5 a vertical section of a modified construction,

Figure 6 a general view showing a complete equipment with a transformer and a contact apparatus and Figure 7 a schematic diagram of 65 connections of the embodiment shown in Figure 1.

With reference to the diagrammatical embodiment illustrated in Figures 1 and 7 the rectifier substantially comprises two parts, namely 70 an alternating current transformer A and a contact apparatus B electrically connected therewith. The transformer A may be a two-phase or a poly-phase transformer adapted to convert the incoming alternating current to a rotating current and also to transform the voltage of the alternating current to a higher or lower value if necessary. In the embodiment shown in the drawings the transformer A consists of a cylindrical iron core, preferably made by a great number 75 of circular plates or sheets, which are associated to form a cylindrical core stacking. About half-way between the periphery and the centre of the cylinder I provide borings 10 adapted to receive the transformer windings. The primary 80 or the alternating current windings (shown in Fig. 7 at 90) may be similar to the stator winding of an induction motor for the voltage and type of current to be rectified. Also the secondary windings, indicated at 11, are arranged 85 in the borings 10 but are electrically insulated from the primary and may be connected similar to the armature coils of a two-pole direct current motor of the wellknown type. The windings 11 are provided with points of connection 90 12—19, the number of which corresponds to the number of the commutator segments of the contact apparatus B. If the secondary windings comprise several windings, they may be connect- 95 ed in series or in parallel.

In operation, alternating current is supplied to the primary 90 of the transformer thereby producing in the secondary winding 11 a multi-phase current, rotating at a speed corresponding to the frequency of the primary alternating current. 105 Assuming that the primary current has a frequency of 50 periods per second the multi-phase current in the secondary winding 11 will rotate at a speed of 3000 revolutions per minute. It will be obvious that if a pair of sliding contacts 110

cooperating with the points 12—19 are caused to rotate synchronously with the said multi-phase current, a pure direct current may be delivered from the sliding contacts. It will also be obvious that the highest potential difference of the multi-phase current is established between two diametrically opposite points of the winding 11, say between points 12 and 16, 13 and 17 etc.

In order to accomplish the synchronous movement of the contacts practically I provide the contact apparatus B comprising a frame 20 carrying two pairs of fixed electro-magnets 21, 23 and 22, 24 respectively, the magnets of each pair being arranged diametrically one opposite the other. The magnets are provided with diagrammatically indicated windings or coils 21^a, 22^a, 23^a, 24^a and current is supplied to each pair of the coils 21^a, 23^a and 22^a, 24^a from a pair of diametrically opposite points of the secondary 11, said pairs of points being displaced one from the other at an angular distance of 90°. By way of example, the points 14 and 18 may supply current to coils 21^a and 23^a, whilst points 12 and 16 may supply current to coils 24^a and 22^a (Figure 7). The connecting wires extending from the selected points of the secondary 11 to the field coils of the contact apparatus are not shown in Figure 1 but for sake of simplicity the connecting terminals 12^a, 16^a, 14^a, 18^a of the field coils 24^a, 22^a, 21^a, 23^a in this figure are designated in such way that the proper connections are obtained by connecting the said terminals with those points of the secondary designated with corresponding reference numerals (12, 16 and 14, 18 respectively). As shown in Figures 1 and 7 each pair 21^a, 23^a and 22^a, 24^a of the field coils are also associated by means of conductors, connecting the coils so as to provide opposite magnetic poles at the upper ends of the magnets in each system 21, 23 and 22, 24 respectively, i. e. if magnet 21 has positive pole, magnet 23 has negative pole at the upper ends.

The contact body of the contact apparatus comprises a polarized armature and one or several contact rollers engaging with suitable commutators. The armature 25 which is arranged in the space between magnets 21, 22, 23 and 24 is surrounded by a stationary solenoid 26 preferably fixed to the frame 20. The connecting terminals 27, 28 of the solenoid 26 are supplied with direct current, which in starting the rectifier may be delivered from a battery or another external source of energy and during the working of the rectifier the direct current may be supplied from the current rectified by the rectifier. By the influence of the flux from the solenoid 26 the armature 25 obtains a determined and constant magnetic polarity. The armature is attached to a shaft 29 carrying two contact rollers 30, 31, which are rotatably mounted on the shaft but electrically insulated therefrom. The rollers 30, 31 are provided with conical extensions 32, 33 tapering downwardly and surrounded by seats 34, 35, which have conical inner surfaces and are formed in brackets on the frame 20.

The contact rollers 30, 31 are adapted to roll in the inner contact surfaces of the commutators 36, 37, attached to the frame 20 and comprising eight segments 12^b—19^b which are obliquely arranged and insulated from one another. By conductors (shown in Figure 7) each segment is connected with a selected one of the points 12—19 of the transformer A, segment 12^b being connected to point 12, segment 13^b being connected to point 13 etc. As will be apparent from

the drawings each segment of the upper commutator 36 is connected with the same point of the secondary winding 11 of the transformer as the diametrically opposite segment of the lower commutator 37. In other words, the upper and lower segments are displaced an angle of 180° in relation to one another.

In the position of rest of the apparatus the conical extensions 32, 33 engage the conical seats 34 and 35 and in this position the centre of the armature 25 preferably is situated below a horizontal plane through the centres of the magnets 21—24. The solenoid 26 is provided with a spacious centre bore enabling the armature 25 to move freely within determined limits. A corresponding air gap is provided between the inner contact surfaces of the commutators 36, 37 and the contact rollers 30, 31.

In starting the apparatus, alternating current is supplied to the primary of the transformer A and as a result of the induction produced in the iron core by the said alternating current, a multi-phase current is generated in the secondary winding 11. From the points 12—19 the multi-phase current is supplied to the corresponding connecting terminals 12^a—18^a of the field coils and to the segments 12^b—19^b of the commutators 36 and 37. At the same time direct current is supplied from any source of energy to terminals 27, 28 of the solenoid 26. The multi-phase current supplied to field coils 21^a—24^a from transformer A produces a rotary field which will tend to move the armature 25 polarized by the flux of the solenoid 26. Since the centre of the armature lies below the centres of the magnets, the armature will try to rise simultaneously as its centre of gravity, under the action of the rotary field, has the tendency to move in a circular path at a speed which is synchronous with the velocity of the multi-phase current, for instance 3000 revolutions per minute. As a result of the raising and circular movement the conical extensions 32, 33 are caused to roll in the inner conical surfaces of the seats 34, 35. The pressure against the said conical surfaces produces a vertical component of force, which raises the armature 25 further so that the armature guided by the conical surfaces 34, 35 is permitted to move on a path having a successively increasing radius. It will be obvious that the centre of gravity of the armature will thus be driven by the rotary field synchronously in a helical path the radius of which increases successively from zero to a predetermined value and at the same time the armature is raised under the action of the vertical component of the cone pressure and the vertical field component acting in the same direction. When the radius of the path of movement of the armature 25 reaches a sufficient length the contact rollers 30, 31 engage the inner contact surfaces of the commutators 36, 37 in which they continue to roll synchronously with the frequency of the alternating current in the primary of transformer A.

Figure 1 illustrates diagrammatically that the conical extensions 32, 33 electrically associated with the contact rollers 30, 31 are connected with current collectors 38 and 39. In working condition the contact rollers 30, 31 are rotating synchronously with the current in the secondary 11 of the transformer A, and at the same time engaging the segments 12^b—19^b connected with selected points of the said secondary. Since the rollers in operative position, engage the commutators and rotate synchronously with the current

in the secondary 11 and since this current is supplied to the commutators a pure direct current can be collected at the current collectors 38, 39. It should be remembered that the polarity of the upper collector 38 is always opposite to the polarity of the lower collector 39, owing to the fact that each segment of the upper commutator 36 is displaced 180° to the corresponding segment of the lower commutator 37.

10 By reason of the comparatively heavy pressure between the contact rollers and the contact surfaces of the commutators, the commutation will be effected substantially sparkless even at considerable currents, and, at the same time, the 15 wear of the segments is reduced to a minimum, since the engagement with the contact rollers is effected by means of rolling friction and not by sliding friction. The mechanical loss of the apparatus is very low as the armature has no mechanical support in operative position but is carried 20 by the vertical components of the field and the cone pressure exclusively. These features of the improved rectifier result in a very high efficiency in relation to known types of rectifiers. A 25 further advantage is that the size of the apparatus may be reduced.

In order to prevent an unintended engagement of the conical extensions 32, 33 with the edges of the seats when the conical extensions 32, 33 have 30 been raised from the conical seats 34, 35, I prefer to construct the magnets so as to cause the top of the axis of the armature to incline in an opposite direction to the rolling direction of the contact rollers.

35 Figure 2 illustrates an especial form of the magnets 21—24 to accomplish this result. As shown in the drawings illustrating a magnet in perspective view, the upper right corner 40 of the laminated pole piece is cut away so that the field will 40 be weaker at this edge than at the left edge 41. This deformation of the field causes the upper end of the armature to lag somewhat behind the lower end, provided that the armature rolls in a clockwise direction. In other words, the top of the axis of the armature is caused to incline towards the left. By the reason of this inclined position the tendency of the conical extensions to engage with the edges of the conical seats is avoided. If the rolling direction of the armature is chosen 45 to be effected in a counter-clockwise direction, the upper left corner of the pole piece is cut away to cause the axis to incline towards the rolling direction.

Figure 2 also illustrates that oblique equal large 50 portions are cut away from the lower edges 42, 43 of the pole piece, the upper corner of the right edge 42 and the lower corner of the left edge 43 being removed. This assymetrical form of the pole piece enables the armature to occupy a substantially fixed elevational position during the 55 working of the apparatus, so that the armature is prevented to be raised too much. By bevelling the corners as described the resulting acting line of the field will be situated about at 44 so that the centre of gravity of the armature tends to take up a fixed position to this line, thereby preventing a raising motion over a determined level.

A constructional embodiment of the contact apparatus is shown in Figures 3 and 4, the former being a horizontal section of the contact apparatus, whilst Figure 4 is a vertical section along the lines IV—IV of Figure 3.

The contact apparatus comprises two covers 45, 46 associated together by means of bolts 47 to 60 form a rigid support for the construction. At-

tached by screws 49 to the peripheral part of the covers 45, 46 are the laminated magnets 21, 22, 23, 24, which are surrounded by coils 21a, 22a, 23a, 24a having a suitable number of turns depending upon the voltage used. In the centre of the 80 covers 45, 46 are recesses 51 adapted to receive funnel-like or conical seats or rings 34 and 35. Above seat 34 and beneath seat 35, segment commutators 36 and 37 respectively are provided having conical inner contact surfaces and attached to cylindrical members 54, fixed to the covers 45, 46 by means of bolts 55. Insulating collars 56 are interposed between the members 54 and the commutators 36 and 37.

85 Arranged in the space between the four magnets is an armature 25 which is surrounded by a solenoid 26 rigidly associated with the cover 46 by means of supports 59. As will be apparent from the drawing a horizontal plane assumed to pass through the centre of the solenoid and the magnets lies above a horizontal plane passing through the centre of the armature 25. The armature 25 is fixed to a shaft 29 on which two tubular contact rollers 61 are rotatably mounted but electrically insulated from the shaft by means of insulating members 62. The rollers have conical extensions 32 and 33, the taper of which substantially corresponds to that of the conical seats 52.

90 The electrical connection of the apparatus and the general construction of the transformer 105 (not shown) is similar to that described with reference to Figures 1 and 7. The necessary joints of connection are effected on the panels 64. The direct current is collected from the contact rollers 61 by means of collectors 67 carried by 110 rods 65, which are insulated from the support at 66 and which are connected to the supply networks.

95 The operation of the apparatus is substantially the same as described with reference to 115 Figure 1. Under the action of magnetic and mechanical forces the armature is lifted in a helical path in the conical seats till the radius of the circular movement of the armature increases sufficiently to enable the contact rollers 61 to 120 engage the commutators 36 and 37. By constructing the magnets as described with reference to Figure 2 the tendency of the extensions 32 and 33 to engage with the surfaces of the seats 34 and 35 under working conditions is avoided and the 125 armature is prevented from rising above a determined level.

100 To enable the current to be collected from the contact rollers 61 without preventing the free raising movement of the armature in the starting moment the rods 65 of the collectors 67 are 130 resilient and the collectors are adapted and arranged so as to slide against the inner walls of the tubular contact rollers after starting the contact body.

105 Figure 5 illustrates a vertical section of a further embodiment of the contact apparatus, in which the conical seats are movable. It will be understood that if the seats are lowered in relation to the conical extensions during the starting period, the armature will be permitted to move in a helical path in the horizontal plane without any tendency to rise. The same result may be obtained by arranging the seats displaceably in relation to one another.

110 It will be noted that this arrangement ensures the armature to occupy a fixed elevational position at all times, so that the collecting of the current is facilitated.

115 In Figure 5 the same reference characters re- 150

fer to similar parts as in Figures 3 and 4. The electrical connections and the principal operation is similar to that of the apparatus shown in Fig. 1.

5 The conical movable seats 34, 35 are attached to bolts 68 extending upwardly at 70 and associated by means of the transverse member 69. The movement of the seats is guided by the fixed guides 71, provided with slots 72 in which the 10 seats are mounted to slide vertically. The dotted lines 73 indicate the lowest position of the lower seat 35, whilst the full lines indicate the upper position of the seats. The current collectors 74, 75 being fixed to the contact rollers 61 are provided with spring means and are adapted 15 to serve as supports for maintaining the armature in a fixed horizontal position. The remaining parts of the contact apparatus are constructed similar to the parts shown in Figures 3 and 4.

20 The operation of the apparatus is the following. The energizing of the magnets by multi-phase current from the transformer A (Figure 1) produces a rotary field tending to move the polarized armature 25, which, however, is prevented from following this movement by the 25 seats 34, 35 in which the conical extensions 32, 33 of the armature rest. If the seats now are lowered by pressing the transverse member 69 downwardly the armature is released and is permitted to roll in a helical horizontal path the 30 radius of which increases successively according as the seats are lowered. When the seats are lowered in a sufficient degree the contact rollers 61 engage the inner surfaces of the commutators 36, 37 in which they continue to roll synchronously with the speed of field. Now the conical seats 34, 35 are lowered further to avoid any 35 risk of engagement of the conical parts 32, 33 with the seats resulting in a sparking commutation.

40 Preferably the lowering movement of the seats 34, 35 is effected positively simultaneously with the supply of current to the apparatus. Figure 6 illustrating a device for this purpose shows a 45 complete equipment with the transformer A and the contact apparatus B. By levers 79, 80, 81 the transverse member 69 shown in Figure 5 is associated with the handle 78 of the starting switch or the starter 77 of the apparatus. By 50 means of a slot 82 in lever 81 the handle 78 is permitted to move within certain limits without affecting said lever. Therefore when the handle 78 of the starter 77 is moved to switch on current the contact knives of the switch are permitted to engage the contacts without moving the lever 81. Only after the knives having 55 reached their contact position thereby switching on current to the system the levers 79, 80, 81 are operated by the handle 78 to lower the seats 34, 35 by means of the transverse member 69 and the bolts 68, thus releasing the armature, which is now free to start its movement in the helical horizontal path.

60 The elevational position of the armature is maintained at a constant level by the resilient current collectors 74, 75.

In stopping the apparatus the seats 34, 35 are raised by the levers 79, 80, 81 and the handle 78 before current is interrupted, so that the armature is ready to occupy its position of rest in the seats as soon as current is switched off. Instead of connecting the seats 34, 35 with the switch 77 mechanically an electro-magnetic device may be used for raising and lowering the 75 seats. The circuit of the said device preferably

is controlled by the starter 77 of the apparatus.

The conical seats 34, 35 also may be displaced in relation to one another for the purpose described but in this event the smallest or the widest end respectively of one cone should be directed towards the smallest or widest end of the other cone. Furthermore, the seats can be mounted on a support actuated by spring means, which are compressed by the movement of the armature, causing a lowering movement of the 80 seats. 85

The armature may have any desirable form and may consist of a permanent magnet instead of being polarized by a solenoid. The contact apparatus also may be arranged so as to permit the axis of the armature to occupy a horizontal position if desired. In this case the necessary pressure for the engagement with the conical seats is exerted by the resilient spring actuated 90 collectors. 95

While a specific embodiment of the invention has been illustrated and described it is to be understood that alterations of the details of construction may be made without departing from the spirit of the invention. 100

Having now fully described my invention, what I claim as new and desire to protect by Letters Patent is:

1. In a rectifier commutating means, a contact body, means producing a rotary field, which 105 drives the contact body at a synchronous speed and means for guiding the contact body during the starting period to cause the said body to move in a helical path to the position where the contact body engages with the commutating 110 means.

2. In a rectifier commutating means, a contact body, means producing a rotary field, which drives the contact body at a synchronous speed, conical parts associated with the contact body 115 and conical seats adapted to cooperate with the said conical parts to guide the contact body in a helical path during the starting period.

3. In a rectifier commutating means, a contact body, means producing a rotary field, which 120 drives the contact body at a synchronous speed, conical parts associated with the contact body and displaceable conical seats adapted to cooperate with the said conical parts to guide the contact body in a helical path during the starting 125 period.

4. In a rectifier commutating means, a contact body, means producing a rotary field, which drives the contact body at a synchronous speed, conical parts associated with the contact body, 130 displaceable conical seats adapted to cooperate with the said conical parts to guide the contact body in a helical path during the starting period, a starting switch, and a coupling mechanically connecting a bovable part of the switch with the 185 displaceable seats.

5. In a rectifier commutating means, a contact body, means producing a rotary field, which drives the contact body at a synchronous speed, conical parts associated with the contact body, 140 displaceable conical seats adapted to cooperate with the said conical parts to guide the contact body in a helical path during the starting period, a starting switch, and a coupling mechanically connecting the handle of the switch with the displaceable seats and adapted to permit loose motion within determined limits between the handle of the switch and the coupling. 145

6. In a rectifier commutating means, a contact body, means producing a rotary field, which 150

- drives the contact body at a synchronous speed, conical parts associated with the contact body, displaceable conical seats adapted to cooperate with the said conical parts to guide the contact body in a helical path during the starting period and an electromagnetic device operating the said conical seats. 80
5. In a rectifier commutating means, a contact body, means producing a rotary field, which drives the contact body at a synchronous speed, conical parts associated with the contact body, displaceable conical seats adapted to cooperate with the said conical parts to guide the contact body in a helical path during the starting period and spring means adapted to support the displaceable seats. 85
10. In a rectifier commutating means, a contact body, means producing a rotary field which drives the contact body at a synchronous speed and which rotates synchronously with the frequency of the alternating current to be rectified, and means for guiding the contact body during the starting period to cause the said body to move in a helical path to the position where the contact body engages with the segments. 90
15. In a rectifier commutating means, a polarized armature, contact members carried by the armature, means producing a rotary field which drives the armature at a synchronous speed, means for guiding the armature during the starting period to cause the armature to move in a helical path to the position where the contact members engage with the commutating means. 95
20. In a rectifier two commutators having a number of segments, means connecting each segment of one commutator with a segment of the other commutator, a contact body, means producing a rotary field which drives the contact body at a synchronous speed and which rotates synchronously with the frequency of the alternating current to be rectified, and means for guiding the contact body during the starting period to cause the said body to move in a helical path to the position where the contact body engages with the segments. 100
25. In a rectifier two commutators having a number of segments, means connecting each segment of one commutator with a segment of the other commutator, a contact body, contact members mounted on the contact body, means producing a rotary field which drives the contact body at a synchronous speed, means for guiding the contact body during the starting period to cause the said body to move in a helical path to the position where the contact members engage with the segments and current collectors associated with the contact members. 105
30. In a rectifier commutating means, a contact body, tubular contact rollers rotatably mounted on the contact body, means producing a rotary field, which drives the contact body at a synchronous speed, means for guiding the contact body during the starting period to cause the said body to move in a helical path to the position where the contact rollers engage with the commutating means and resilient current collectors adapted to cooperate with the inner walls of the tubular contact rollers. 110
35. In a rectifier commutating means, a contact body, contact rollers rotatably mounted on the contact body, means producing a rotary field, which drives the contact body at a synchronous speed, means for guiding the contact body during the starting period to cause the said body to move in a helical path to the position where the contact rollers engage with the commutating means, and current collectors rigidly fixed to the rollers and adapted to cooperate with the rollers. 115
40. In a rectifier commutating means, a polarized armature, contact members carried by the armature, electromagnets arranged around the armature, conductors supplying multiphase current to the magnets, and means for guiding the armature during the starting period to cause the armature to move in a helical path to the position where the contact members engage with the commutating means. 120
45. In a rectifier commutating means, a polarized armature, contact members carried by the armature, electromagnets surrounding the armature and adapted to produce an assymetrical field to cause the top of the axis of the armature to incline towards the rolling direction of the armature, conductors supplying multi-phase current to the magnets, and means for guiding the armature during the starting period to cause the armature to move in a helical path to the position where the contact members engage with the commutating means. 125
50. In a rectifier commutating means, a polarized armature, contact members carried by the armature, electromagnets surrounding the armature and having pole pieces, in which one edge is cut away to produce an assymetrical field to cause the top of the axis of the armature to incline towards the rolling direction of the armature, conductors supplying multi-phase current to the magnets, and means for guiding the armature during the starting period to cause the armature to move in a helical path to the position where the contact members engage with the commutating means. 130
55. In a rectifier commutating means, a polarized armature, contact members carried by the armature, electromagnets surrounding the armature and having pole pieces, in which one edge is cut away to produce an assymetrical field to cause the top of the axis of the armature to incline towards the rolling direction of the armature, conductors supplying multi-phase current to the magnets, and means for guiding the armature during the starting period to cause the armature to move in a helical path to the position where the contact members engage with the commutating means. 135
60. In a rectifier commutating means, a polarized armature, contact members associated with the armature, means producing a rotary field, which drives the armature at a synchronous speed, and means for guiding the armature during the starting period to cause the armature to move in a helical path to the position where the contact members engage with the commutating means. 140

ERNST ALBERT EMANUEL TÖRNBLOM.
